UNITED STATES PATENT OFFICE.

ARTHUR M. BURNHAM, OF GARDINER, MAINE, ASSIGNOR, BY DIRECT AND MESNE ASSIGNMENTS, OF ELEVEN-SIXTEENTHS TO MRS. LUTE B. LIBBY, OF GARDINER, MAINE, AND WILLIAM G. CRAWFORD, OF WASHINGTON, DISTRICT OF COLUMBIA.

MAIL-BOX.

SPECIFICATION forming part of Letters Patent No. 718,190, dated January 13, 1903.

Application filed April 22, 1902. Serial No. 104,170. (No model.)

To all whom it may concern:

Be it known that I, ARTHUR M. BURNHAM, a resident of Gardiner, in the county of Kennebec and State of Maine, have invented certain new and useful Improvements in Mail-Boxes; and I do hereby declare the following to be a full, clear, and exact description of the invention, such as will enable others skilled in the art to which it appertains to make and use the same.

My invention relates to an improvement in mail-boxes, and more particularly to private mail-boxes for rural delivery, the object of the invention being to so construct and mount a box of this character that it will be pivotally or rotatively mounted and which will lock but in one position, thereby dispensing with the necessity for a signal, as the position of the box will indicate the presence or absence 20 of mail-matter.

With this object in view the invention consists in certain novel features of construction and combinations and arrangements of parts, as will be more fully hereinafter described, 25 and pointed out in the claims.

In the accompanying drawings, Figure 1 is a top view, partly in section, showing the cover raised and in position to prevent the locking of the cover when closed. Fig. 2 is a view in 30 horizontal section, showing the cover locked. Fig. 3 is a cross-section of Fig. 2. Fig. 4 is a front elevation with the cover partly broken away, and Figs. 5 and 6 are views of details of construction.

1 represents a post or standard to support my improved box and has secured on its upper end by means of screws a plate 2. (Shown in detail in Fig. 6.) This plate is provided centrally with a vertical stud 3, and near its 40 edge holes or sockets 4 are located a distance apart about equal to one-fourth of the circumference of the plate for a purpose which will hereinafter appear.

The mail-receptacle 5 is preferably of a 45 general rectangular shape and has a cover 6 hinged thereon, which latter is of a semi-cylindrical shape, flared outward throughout its entire lower edge.

The receptacle 5 is provided centrally with 50 a circular depression or pocket 7, having a

central flanged opening 8^a to receive stud 3 and flanged around its lower edge to inclose plate 2 and revolve around the same, and a strong arm 8 is secured by a set-screw on the upper end of stud 3 in pocket 7, and against 55 which shoulders 9 in the pocket strike and limit the turning of the box.

In a socket 10 in the base of pocket 7 a pin 11 is located and is contracted at its lower end and is adapted to project through the 60 pocket and into either of the holes 4 in plate 2 when the cover 6 is closed, as will now be explained. A coiled spring 12 is located in socket 10 to normally raise the pin 11 out of engagement with plate 2, while a bell-crank 65 lever 13, preferably of spring-wire, fulcrumed between its ends on a pin 14, secured in a recess in receptacle 5, is connected at one end to the pin and at its other or long end projects upward and rearward to be moved by the 70 cover when closed, and thereby force pin 11 into one of the holes 4.

In the cover, at its rear, a metal strip 14^a is secured and is adapted to close the space between the receptacle and cover when the latter is opened, and it is this strip 14^a which first engages the long end of spring-lever 13 during the first part of the closing movement of the cover and locks the box against rotative movement when the cover is closed. 80

In the front portion of receptacle 5 a lock-casing 15 is provided and contains a catch 16, of a general bell-crank shape, the upright member of which is made with a tooth to engage a similar tooth on the end of a bolt 17, 85 secured in the cover, and lock the bolt in the casing. The shorter or horizontal member 18 of the lever is engaged by a flat spring 19, secured at its upper end in the casing and bowed at its lower end, where it engages the free end 90 of member 18, and is adapted to hold the catch in either its locking or unlocking position until overcome by the stronger spring 22, as will now be set forth.

The catch 16 is secured on a shaft 21, supported in suitable bearings and projecting across the pocket 7, and has the strong coiled spring 22 thereon secured at one end to the shaft and having its other end free and extending away from the shaft and slightly 100

downward, so as to ride under arm 8 when the box is turned in one direction and compel the spring to act, and which when the box is turned in the opposite direction will be free to turn with the shaft and exert no spring-pressure thereon.

A suitable key is of course provided to open the box when locked, and shoulders 23 are secured in the cover to support the weight thereof when closed.

A plate 24 is provided to close pocket 7 and the working parts therein and is preferably connected to stud 3 by a screw, as shown.

The operation of my improvements is as follows: When no mail is in the box, it will be turned to a position at right angles to the road and be held in such position by the pin 11, projecting into a hole or socket 4 in plate 2, and the box will be unlocked, as spring 22 cannot 20 not act to hold the catch 16 in its locking position. When mail is placed in the box, the latter given a quarter-turn and closed, moving the free end of spring 22 beneath arm 8, the spring will exert a strong pressure on catch 25 16 to hold it in engagement with bolt 17 and secure the cover in its closed position until unlocked by a suitable key, as above explained. It will thus be seen that with this improved box no signal is required, as the position of the box will indicate the presence or 30 absence of mail.

A great many slight changes and alterations might be made in the general form and arrangement of parts without departing from 35 my invention, and hence I do not wish to be limited to the precise construction set forth, but consider myself at liberty to make such slight changes and alterations as fairly fall within the spirit and scope of my invention.

Having fully described my invention, what I claim as new, and desire to secure by Letters Patent, is—

1. In a mail-box, the combination with a movable receptacle and a closure therefor, of 45 a lock for said closure and mechanism in the box only operative when the box is in one position to compel the operation of the locking mechanism.

2. In a mail-box, the combination with a 50 receptacle mounted to turn and a closure for said receptacle, of a catch in said receptacle to engage a bolt on the closure, and mechanism in the receptacle in operation only when the box is moved to one position, and adapted 55 to hold the catch in its locking position.

3. In a mail-box, the combination with a 60 vertical stud and a mail-receptacle pivoted thereon and into which the stud projects, of an arm on the stud in the box, stops in the 65 box to strike the arm and limit the turning of the box and locking mechanism for said box.

4. In a mail-box, the combination with a 65 vertical stud and a mail-receptacle pivoted

thereon and into which the stud projects, of 65 an arm secured on the stud and located in the box, stops in the box to engage the arm and limit the turning of the box, a closure for said receptacle, a catch to lock the closure, and a spring to operate said catch when the box is 70 moved to a position to project the spring beneath the arm.

5. In a mail-box, the combination with a mail-receptacle, a stud projecting into said receptacle on which it turns, a cover for said receptacle and a bolt on said cover, of an arm secured on the stud in the receptacle, a catch in the receptacle, a spring to hold the catch in either its locked or unlocked position and another spring to overcome said 80 first-mentioned spring and hold the catch in its locked position when the box is turned to project one end of said last-mentioned spring beneath the arm.

6. In a mail-box, the combination with a 85 receptacle for mail, a stud pivotally supporting the receptacle and projecting thereinto, a cover for the receptacle and a bolt thereon, of a shaft in the receptacle, a catch secured on the shaft and adapted to lock the bolt, a 90 flat spring engaging the catch to hold it in either its locked or unlocked position, a coiled spring on the shaft having one end secured thereto and the other free and projecting away from the shaft and said spring only 95 operative to hold the catch in its locking position when the box is moved to project the free end of said spring beneath the arm.

7. In a mail-box, the combination with a support and a plate thereon, of a stud on said plate, a mail-receptacle mounted to swing on the stud, a spring-elevated pin in the receptacle, and a spring-lever operated by the cover when the latter is closed, to force the pin into 100 holes in the plate and secure the box against 105 rotation.

8. In a mail-box, the combination with a pivotal support, of a pin to lock the box in either of two positions, and mechanism operated by the cover in closing to force this 110 pin to its locking position.

9. The combination of a mail-box pivotally supported to turn in a horizontal plane and constitute in itself a signal according to the position which it is made to assume, a lock 115 and devices coöperating with the box and said lock to cause the latter to lock the box only when said box is in position to indicate that it contains mail and to prevent the locking of the box when it is in position to indicate 120 that the box is empty.

In testimony whereof I have signed this specification in the presence of two subscribing witnesses.

ARTHUR M. BURNHAM.
